UNITED STATES PATENT OFFICE

109,440

DESIGN FOR A TEXTILE FABRIC OR SIMILAR ARTICLE

Ivan Sluizer, Amsterdam, Netherlands

Application April 5, 1938, Serial No. 76,298

Term of patent 3½ years

To all whom it may concern:

Be it known that I, Ivan Sluizer, a subject of the Kingdom of the Netherlands, residing in Amsterdam, Netherlands, have invented a new, original, and ornamental Design for a Textile Fabric or Similar Article, of which the following is a specification, reference being had to the accompanying drawing, forming part thereof.

The figure is a plan view of a textile fabric showing my new design.

The figure shows a complete design unit which

is repeated in regular succession over the fabric.

The characteristic feature of the design consists of ray-like elements radiating from each corner of the design unit which meet to form chevron-like elements, the apex of which point toward the center of the design unit.

I claim:

The ornamental design for a textile fabric or similar article as shown and described.

IVAN SLUIZER.
